CLAIM

The ornamental design of a badge shield, as shown and described.

DESCRIPTION

FIG. 1 is a front elevational view of a badge shield showing my new design;

FIG. 2 is a rear elevational view;

FIG. 3 is a side elevational view, the opposite side being a mirror image;

FIG. 4 is a sectional view taken along the lines 4—4 of FIG. 1;

FIG. 5 is a front elevational view of a badge shield showing a second embodiment of my new design;

FIG. 6 is a side elevational view thereof, the opposite side being a mirror image;

FIG. 7 is a rear elevational view thereof; and

FIG. 8 is a sectional view taken along the lines 8—8 of FIG. 5.
